(57) **CLAIM**

The ornamental design for a female urinal, as shown and described.

DESCRIPTION

FIG. 1 is a perspective view of a female urinal showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

FIG. 9 is a perspective view of the female urinal in a first collapsed position; and,

FIG. 10 is a perspective view of the female urinal in a second collapsed position.

The broken lines depict portions of the female urinal that form no part of the claimed design.

1 Claim, 10 Drawing Sheets
